CONTAINER

Malcolm S. MacNaught, Yonkers, N. Y., assignor
to Hixon Electric Co., Boston, Mass., a cor-
poration of Massachusetts

Application August 17, 1932, Serial No. 629,134

3 Claims. (Cl. 229—87)

This invention relates generally to protective means for mechanical and electrical hardware and equipment, and especially such equipment of building hardware and electrical installations of various kinds as is intended for use and assembly with other elements, and my invention is intended as a protection and means for display for such material from the time of manufacture at the factory to the completion of the work on which it is to be used.

In the drawing of one embodiment of my invention selected for description and illustration herein:—

Fig. 1 is a development of the blank from which, by folding, a typical protective container or wrapper is made;

Fig. 2 is a perspective of such a wrapper or container folded, with the article therein;

Fig. 3 is a perspective of a portion of an electric switch block, for illustrative purposes only, for a portion of which my novel container provides a protective covering;

Fig. 4, a development of the blank for protecting, by suitable folding, such member;

Fig. 5, a perspective of the folded protector or container therefor; and

Fig. 6, a perspective of a folded container for a conventional duplex receptacle plate.

Fig. 7, a perspective detail of a portion of the folded container, with the switch handle 18 projected through the slot 16 in the container, and the hood 28 thereover.

Referring first to Fig. 1, my novel, illustrative protective and display container, of regenerated cellulose sheeting, paper or other suitable and preferably transparent material, is shown as embodied in a blank for the reception of a wall switch plate for an electric switch, and comprising a bottom panel 1 with laterally extended wings 2, 3 thereon, creased or indented if desired at 4 for folding along lines preferably corresponding to the edges of the plate to be received therein.

The bottom panel 1 is scored or perforated along the line 5, so that the section outlined thereby may be raised at one end from the bottom panel, folded back upon itself on line 6, caused to adhere along its edges to the remaining portion of the scored section by means of an adhesive strip 7, and thus form a pocket 8 for receiving screws 9, Fig. 2, to be used to secure the switch plate to the wall. This pocket will remain attached to the bottom panel 1, at the opposite panel end, as shown in Fig. 2, and may be detached at will along a serrated line, for instance, at 99, Fig. 1. On its ends, the blank 1 is also provided with wings or

tabs 10, 11, each provided preferably with suitable adhesive areas, as in the form of strips 12, as is also the wing 2.

This wing 2, in this case, is also provided with apertures 13, 14 to register, respectively, with the apertures 15, 16 in the switch plate 17, Fig. 2, to be enclosed in the container, the apertures 15 to receive the screws 9 for securing the plate to the wall and the latter aperture to receive the tumbler or switch handle 18 (Fig. 3), if any. If the plate has no aperture, and is perfectly plain, no aperture 16 is needed. If the plate, as a receptacle plate 19, Fig. 6, of the duplex type is to be wrapped, the end wings 10, 11 are made long enough to cover them when infolded. At any suitable point on the edge of the blank, it may be also provided with a suitable complementary pocket-forming blank 20 for the switch post or tumbler, to be described.

In use, the conventional switch plate 17, for instance, when made at the factory, Fig. 2, is laid flat upon the bottom panel 1 of the container with its edges registering with the line 4. The wing 3 is first laid over and upon the top of the plate, the wing 2 is then laid over and upon the wing 3, and the wings 10, 11 are afterwards laid over upon the wings 2, 3 and each of the wings caused to adhere to the member below it by a suitable adhesive strip or area 12, see Fig. 2.

The plate 17 is then turned over, the pocket 8 for the screws formed as described, with the screws placed therein, leaving a portion of the back of the container open to receive, for instance, the switch tumbler 18 when installed.

The conventional switch block 21 frequently used with the plate 17 is shown in Fig. 3. To cover and protect the tumbler 18 in the same manner that the plate is protected as described, the wing blank 20 is removed from the blank 1 along the scored line 201, giving the auxiliary blank shown in Fig. 4.

The wings 22 of the blank 20, Fig. 5, are then folded, Fig. 4, downwardly along scored lines 23, the wings 24 are folded on the scored lines 25 and the auxiliary wings 26 along the lines 27, forming a post or tumbler-shaped container or hood 28, which can be slipped over and upon the tumbler 18.

In this manner, the plate 17 and tumbler 18 are packed at the factory and protected while they are in stock, but the style and finish of the parts are clearly observable through the container, for selection purposes.

When the parts are received at the place of construction, where they are to be used, they

are likewise protected and examinable until wanted.

When the walls of the building, for instance, are up so that the plates and switch boxes with tumblers therein can be placed in position, they are assembled with the containers still on them. The pocket 8 is severed from the back 1 along line 99, screws 9 removed therefrom, inserted in the apertures 15, the ends of flaps 10, 11 being 10 lifted for that purpose, and then replaced. The plate is put into position with the tumbler 18 extended through the slot 16, but protected by its hood. The ends of the flaps 10, 11, may then be gummed to the member 1 by means of the 15 short gummed strips 12 to protect the screw heads.

The assembled unit is in this manner all installed at once, and no second or third visit from the electrician or other craftsman is required. 20 The unit is protected from paint, grease, dirt and damage until the work is complete. When the proper time comes, the front of the container is removed by simply raising the flaps 2, 3, 10, 11, breaking their gummed seals, and tearing them off along the lines of the plate edges, leaving the 25 portions of the back panel 1 in position beneath the plate, which is left fully exposed, clean and undamaged. The hood-like container 20 for the tumbler is removed by pulling the latter from the 30 tumbler.

Fig. 6 shows in perspective a modified form of container adapted for duplex receptacle plates, with openings 29 therefor.

In this manner, door strike plates, escutcheon plates and the like, for any use, as well as other 35 similar articles, may be fully protected from damage, in stockrooms, and packing cases, in transit and after installation, until it is desired to use them.

My invention is not restricted to the precise 40 embodiment thereof herein shown and described.

I claim:

1. A container of transparent material for an

electric fixture having a base panel, end and side wings thereon one at least of which has fixture mounting apertures therein, cooperatively foldable over and with the base panel, a pocket for fixture-mounting elements formed from and attached to the base panel, the end wings, while foldable, being adjustable to enable a fixture-mounting element to be inserted through an aperture in one end wing, the container having an open area in its base panel permitting installation of the fixture on the work and reception of a fixture-cooperating element while still in the container and with the protection thereof. 10

2. A container-forming blank of transparent sheet material, comprising a base panel area, end and side adhesive wings cooperatively foldable thereon to cover the base, one of which wings has a plurality of apertures to receive mechanical locking elements for installing said folded blank and its contents upon a support; 15 a scored adhesive-carrying area in the base panel severable sufficiently from the base and foldable on itself to adhere and form a pocket to receive temporarily said locking elements. 20

3. A container-forming blank of transparent sheet material comprising a base panel area having end and side adhesive wings cooperatively foldable thereon to form the container, one wing having a plurality of apertures for receiving mechanical locking elements to secure the container 30 and contents to a support and an aperture to receive a part of the contained article; a scored adhesive-carrying area in the base area severable sufficiently from the base and foldable on itself to be secured along a plurality of its edges 35 to the scored area to form a closed pocket for said locking elements; and a supplementary separable wing on the blank, foldable to form a hood-like cover for said part of the contained article in one of the apertures and of a construction to project through the aperture when the 40 article is assembled with the container.

MALCOLM S. MACNAUGHT.
